CLAIM

We claim the ornamental design for a housing for a test chip, as shown.

DESCRIPTION

FIG. 1 is a front view of the housing for a test chip of the invention in an open position.

FIG. 2 is a back view of the housing for a test chip of FIG. 1.

FIG. 3 is a top view of the housing for a test chip of FIG. 1.

FIG. 4 is a bottom view of the housing for a test chip of FIG. 1.

FIG. 5 is a side view from the right in an open position of the housing for a test chip of FIG. 1.

FIG. 6 is a side view from the left in an open position of the housing for a test chip of FIG. 1.

FIG. 7 is a perspective view of the housing for a test chip of FIG. 1.

FIG. 8 is a front view of the housing for a test chip of the invention in a closed position.

FIG. 9 is a back view of the housing for a test chip of FIG. 8.

FIG. 10 is a top view of the housing for a test chip of FIG. 8.

FIG. 11 is a bottom view of the housing for a test chip of FIG. 8.

FIG. 12 is a side view from the right of the housing for a test chip of FIG. 8.

FIG. 13 is a side view from the left of the housing for a test chip of FIG. 8; and,

FIG. 14 is a perspective view of the housing for a test chip of FIG. 8.
